EXPANSION CLOSURE PLUG

Archibald Ray McWherter, Peoria, Ill.

Application April 28, 1947, Serial No. 744,461

6 Claims. (Cl. 220—24.5)

1

This invention relates to expansion closure plugs and has particular relation to a novel, improved compressible or deformable closure disk which is readily adapted for use as a blow-out plug in an opening in the block of an internal combustion engine.

It is well known to provide a blow-out plug or expansion disk for an opening provided on a water jacket of an internal combustion engine so that when the water or other liquid in the water jacket freezes and expands, the blow-out plug will be forced outwardly, thereby permitting the solidifying liquid to further expand out of the opening and releasing pressure on the solidifying liquid. The blow-out plug acts as a safety valve to prevent the water jacket and motor block from being cracked by the force of expansion of the solidifying liquid.

Previous blow-out plugs conventionally comprise a concave metal disk which is positioned in the outer annular shoulder of a water jacket opening with the concave side facing the opening. The blow-out plug is normally press-fitted into the annular shoulder by dimpling the outer, convex side with a hammer blow, thereby expanding the plug or disk to fit snugly and be crimped against the annular shoulder. Due to modern automotive design, the motor block has become increasingly inaccessible and it has become extremely difficult, if not impossible, for mechanics to install the conventional plug, one reason being that there is insufficient space between the motor and the sides of the vehicle to permit striking a hammer blow of sufficient force to properly dimple the plug. Moreover, due to such inaccessibility and lack of working space it is often necessary for the mechanic to strike a number of hammer blows thereby causing an insecure and distorted press fit between the plug and the shoulder of the opening.

An object of the present invention is to provide an expansion closure plug which is adapted for use as a blow-out plug for installation in an opening in the block or water jacket of an internal combustion engine.

Another object of the invention is to provide a compressible or deformable closure plug which may be dimpled and expanded in the block opening without the necessity of using a hammer blow.

Still another object of the invention is to provide an expansion closure plug which may be compressed and expanded by locking means forming, in combination, a part of the closure plug.

A further object is to provide an expansion closure plug which may be adjustably compressed and expanded to any desired degree of compression and expansion.

A still further object of the invention is to provide an expansion closure plug which requires a minimum amount of working space to be installed in a motor block opening of an automobile engine.

These and other objects of the invention will be readily understood by reference to the follow-

ing description and accompanying drawing, in which

Fig. 1 is a sectional view showing a closure plug embodying the present invention placed in the annular shoulder of a motor block opening prior to installation;

Fig. 2 is a sectional view of the closure plug after being installed by compression and expansion;

Fig. 3 is a sectional view of a conventional type blow-out plug shown prior to installation;

Fig. 4 is a sectional view of the conventional blow-out plug as installed by dimpling;

Fig. 5 is a sectional view of a modified form of the present invention, and

Fig. 6 is a sectional view showing a further embodiment of the present invention.

Referring now to the drawing, there is shown a cylinder plug 10 provided with an annular opening 11 having an outer annular inset shoulder 12. In the embodiment shown, the expansion closure plug 20 comprises an annular closure disk 21 having a concave face 22, a convex face 23, a central opening 24 and an outer edge 25 or periphery 25. Positioned in the central opening 24 is the locking means in the form of a lock member or bolt 30 preferably provided with a washer 31. In the embodiment shown in Figures 1 and 2, the head of the bolt 30 is positioned opposite the concave face 22 of the closure disk 21. It will be apparent that the face 23 need not be convex in shape.

A locking disk 40 is threadably mounted on the bolt 30. The locking disk 40 is provided with a face 41, which may be either concave or flat (not shown), and a threaded central opening 42. The locking disk is designed to have an outer periphery 43 which is of smaller dimension than the outer periphery 25 of the closure disk 21. The locking disk 40 is mounted on the locking member 30 so that its concave face 41 is adjacent to and opposing the concave face 22 of the closure disk 21.

One feature of the invention is that the locking disk 40 is constructed to possess the property of being relatively incompressible and deformable with respect to the relatively compressible and deformable closure disk 21. Thus, when the deformable closure disk 21 is drawn against the relatively non-deformable locking disk 40, the closure disk 21 may be deformed to expand and dimple, whereas the locking disk will remain rigid and retain its shape.

In operation, when the locking member 30 is threaded into the locking disk 40, the portion of the closure disk 21 adjacent the locking disk 40 is drawn against the concave face 41 of the locking disk, thereby dimpling the closure disk 21 at its point of contact with the locking disk. This compressing and dimpling of the closure disk 21 causes it to expand so that the outer periphery 25 is snugly and securely press-fitted against the inset shoulder 12 of the motor block opening 11. It has been found that the dimpling operation may be improved by providing the locking disk

with a serrated contact portion 44 to increase frictional engagement between the locking disk 40 and the concave face 22 of the closure disk 21.

It will be apparent that the degree of compression, expansion and dimpling may be controlled readily by the number of turns applied to the bolt 30. This results in the advantage that the desired degree of press-fit may be obtained.

In the embodiment shown in Figure 5 the locking member 30 is provided with a nut 32 and is positioned so that the nut 32 is on the outside of the opening and available to the mechanic for tightening, the head 33 of the bolt being adjacent the locking disk 40. It will be apparent that when the nut 32 is tightened toward the head of the bolt, the closure disk 21 will be compressed, expanded and dimpled against the concave face of the locking disk 40.

In a further embodiment of the present invention, as shown in Figure 6, the locking disk forms an integral part of the locking member 30, the latter being provided with a nut 32 positioned adjacent the closure disk 21. It will be apparent that as the nut 32 is tightened, the closure disk 21 will be compressed, expanded and dimpled against the concave face of the locking disk 40. It will be apparent also that suitable washers may be utilized to prevent leakage.

While the invention has been shown and described in its preferred embodiments, changes and modifications will be obvious to those skilled in the art and it is, therefore, my intent to cover all such changes and modifications as fall within the spirit and scope of my invention.

I claim as my invention:

1. An expansion closure plug comprising, in combination, a permanently deformable closure disk provided with a concave face and a central opening, a relatively non-deformable locking disk provided with a concave face and having an appreciably smaller diameter than that of said closure disk, and a threaded locking member extending through said opening, said disks being mounted on said locking member with their concave faces opposing one another, and means cooperating with said threaded locking member for drawing the disk members together, to deform said closure disk whereby the central portion of its concave face becomes convex and is in contact with the concave face of the locking disk.

2. An expansion closure plug comprising, in combination, a permanently deformable closure disk provided with a concave face and a central opening, a relatively non-deformable locking disk provided with a central opening, a concave face having an appreciably smaller diameter than that of said closure disk and a locking member comprising a threaded bolt and nut, said bolt extending through said openings, said disks being mounted on said locking member with their concave faces opposing one another, and said nut and bolt being adapted for movement for drawing the disk members together to permanently deform said closure disk whereby the central portion of its concave face becomes convex and is in contact with the concave face of the locking disk.

3. An expansion closure plug comprising, in combination, a permanently deformable closure disk provided with a concave face and a central opening, a threaded locking member extending through said opening, said locking member terminating at one end in a relatively non-deformable locking disk portion having a concave face

and having an appreciably smaller diameter than that of said closure disk, a threaded nut mounted on the other end of said locking member, said closure disk being mounted on said locking member with its concave face opposing the concave face of the locking disk portion, said locking member being adapted for cooperative movement with said nut for drawing said disk members together, to permanently deform said closure disk whereby the central portion of its concave face becomes convex and is in contact with the concave face of the locking disk.

4. An expansion closure plug comprising, in combination, a permanently deformable closure disk provided with a concave face and a central opening, a relatively non-deformable locking disk having an appreciably smaller diameter than that of said closure disk, and a threaded locking member extending through said opening, said disks being mounted on said locking member with the edge of the locking disk in abutment with the concave face of the closure disk, and means cooperating with said locking member for drawing the disk members together to permanently deform said closure disk whereby the central portion of its concave face becomes convex and is in contact with the concave face of the locking disk.

5. An expansion closure plug comprising, in combination, a deformable closure disk provided with a concave face and a central opening, a relatively non-deformable locking disk provided with a concave face and having an appreciably smaller diameter than that of said closure disk, and a threaded locking member extending through said opening, said disks being mounted on said locking member with their concave faces opposing one another, and means cooperating with said threaded locking member for drawing the disk members together, to deform said closure disk.

6. A detachable closure seal for circular bore holes terminating at a shoulder comprising a dished sealing member formed of flexible sheet material adapted to be inserted in the bore hole with the convex side outwardly and the marginal portion of the member positioned upon the shoulder, said sealing member being formed with a central aperture only and being otherwise imperforate, a rigid, non-flexing disk of a diameter less than the shouldered portion of the hole engaging the concave side of said sealing member in spaced relation from the periphery thereof, screw means carried by said rigid disk and extending through said central aperture in the sealing member and being cooperable when tightened to flex the central portion of the sealing member inwardly and move the marginal portion of said member radially outwardly into effective sealing engagement with the inside of the bore hole.
